G. AUER.
ADJUSTABLE SIGN AND LIGHTING POST.
APPLICATION FILED NOV. 24, 1914.

1,144,629.

Patented June 29, 1915.

UNITED STATES PATENT OFFICE.

GEORGE AUER, OF WHITE PLAINS, NEW YORK.

ADJUSTABLE SIGN AND LIGHTING POST.

1,144,629.

Specification of Letters Patent. Patented June 29, 1915.

Application filed November 24, 1914. Serial No. 873,845.

To all whom it may concern:

Be it known that I, GEORGE AUER, a citizen of the United States, residing at White Plains, in the county of Westchester and State of New York, have invented certain new and useful Improvements in Adjustable Sign and Lighting Posts, of which the following is a specification.

The object of this invention is to provide 10 a durable, attractive and inexpensive sign and lighting post, the arms of which are adjustable to any angle of road intersection and which is not rendered unsightly by the formation of rust stains on the surface of 15 the concrete.

With these ends in view, the invention resides in the construction of the post proper, in the manner of attaching the sign arms, and in the various features of construction 20 and combinations of parts hereinafter described and more particularly pointed out in the appended claims.

In the drawings illustrating the invention: Figure 1 is a perspective view of a 25 form of the post erected with its lower portion embedded in the ground; Fig. 2 is an elevation on a larger scale, the body of the post being broken away at an intermediate region for economy of space; Fig. 3 is a 30 vertical sectional view, taken at the upper part of the post; Fig. 4 is a vertical sectional view, indicating more clearly the rotatably adjustable mounting of the upper arm-bearing section; Fig. 5 is a horizontal section 35 through the post body; Fig. 6 is a horizontal section through the rotatable upper section; and Fig. 7 is a fragmentary elevation of the upper portion of a modified form of post.

The body 2 of the post is a tapering concrete monolith, circular in cross-section and having suitable deformed rods 3 embedded longitudinally therein and serving as reinforcements.

A pipe 4, constituting an electric conduit, 45 is embedded axially in the post body, with a laterally bent lower portion 5 emerging from the side of the post below the ground level, where it is connected by a coupling 6 with a conduit section 7 carrying the wires 50 8 from the nearest line-bearing post or other available source of current. The upper portion 9 of the conduit projects as an extension above the top of the body, to serve as a pivot for a rotatable upper section 10. The latter 55 is also a cast concrete element containing re-

inforcements 11, and is formed with an axial opening 12 receiving the conduit extension 9.

The body 2 is formed just below its upper end with an opening 13 extending transversely through its interior at one side of 60 the conduit 4.

A double sign arm 14, preferably of wood, is made with a wider portion 15 projecting at one side of the post and a narrower portion 16, which is received with a sliding fit 65 in the opening 13 and projects at the opposite side of the post.

A locking strip 17 is screwed or nailed to the edge of the narrower portion 16 outside of the opening 13, and is preferably of the 70 same thickness as the arm and of such vertical width as to make the two arm portions appear the same size. In this way the arm is securely held in place without the use of metal fastenings to form rust streaks on the 75 concrete under the action of the weather. The rotatable section 10 is also formed with a transverse opening 18 at one side of the axial opening 12, and in this opening is mounted a double arm 19 having wider and 80 narrower portions like the member 14 and a locking strip 20 applied after the manner of the strip 17 to the narrower portion. When the arms are painted the junction with the locking strips is rendered invisible. 85

The arm-bearing section 10 is fixed at any angle of adjustment by suitable means engaging the upper end of the conduit extension 9, for example, the coupling 21 shown in Fig. 3, which receives the socket 22 of the 90 incandescent lamp 23. The light is completed by a holder 24, which is apertured for the reception of the conduit extension 9 and clamped between the coupling 21 and the top of the rotary section 10, and a globe 25 95 mounted in the holder and inclosing the lamp. When the member 21 is screwed down the rotary section 10 is clamped to the top of the post body 2, and in this way held rigidly against turning. Before the parts are tightened up the said section with its arm 19 may be turned at any angle, with reference to the lower arm 14, which may be necessitated by the angle of intersection of roads. Fig. 7 shows an expedient which may be adopted when an additional arm is required. In this case the electric conduit is extended above the rotary section 10 or a further extension 26 may be united thereto by a coupling 27, and upon such project. 110

ing portion an arm 28 is rotatably mounted by means of suitable sockets 29. This arm, as well as the arm-bearing section 10, may be clamped in the desired positions by means 5 such as shown in Fig. 3.

What I claim as new is:

1. An adjustable sign and lighting post, comprising a reinforced cast concrete body portion having an opening extending trans- 10 versely therethrough at the top, an electric conduit embedded longitudinally in said body portion and passing at one side of said transverse opening and having an extension projecting above the upper end of the body 15 portion, a rotatable short reinforced cast concrete upper section having a longitudinal opening receiving said conduit extension and further provided with an opening formed transversely therethrough at one 20 side of said longitudinal opening, sign arms extending through and locked in said transverse openings, and an electric illuminating device at the top of said conduit.

2. An adjustable sign and lighting post, 25 comprising a reinforced cast concrete body portion, an electric conduit embedded longitudinally in said body portion and having an extension projecting above the upper end

thereof, a rotatable short reinforced cast concrete upper section having a longitudinal 30 opening receiving said conduit extension and further provided with an opening formed transversely therethrough at one side of said longitudinal opening, a transverse sign arm held in said transverse opening, and an electric illuminating device at the top of said conduit. 35

3. In a concrete sign post, the combination of a concrete post member having an opening formed transversely therethrough, 40 a sign arm having a wider portion projecting at one side of the post member and a narrower portion passing through said opening and projecting at the opposite side, and a locking piece applied to the edge of the 45 projecting narrower portion and making it substantially the same width as the projecting wide portion.

In testimony whereof I have signed my name in the presence of two subscribing 50 witnesses.

GEORGE AUER.
